UNITED STATES PATENT OFFICE.

WILLIAM BLACKMORE, OF SHARON, PENNSYLVANIA, AND ARTHUR JAMES BAZELEY AND DAVID ROBINSON, OF CLEVELAND, OHIO, ASSIGNEES TO NATIONAL MALLEABLE AND STEEL CASTINGS COMPANY, OF CLEVELAND, OHIO, A CORPORATION OF OHIO.

CAR COUPLER.

Application filed January 16, 1925. Serial No. 2,816.

Fig. 1 is a plan partly in section of a coupler embodying our invention with the parts in locked position; Fig. 2 is an elevation with the parts as shown in Fig. 1; Fig. 3 is an elevation similar to Fig. 2, but with the lock in unlocked position and about to go into lock-set position; Fig. 4 is a plan, partly in section, but with the lock in lock-set position; Fig. 5 is an elevation similar to Figs. 2 and 3 but with the lock in lock-set position; Fig. 6 is a section on line VI—VI of Fig. 4; Fig. 7 is a plan, partly in section, of a pair of couplers with the lock of the left hand coupler in lock-set position; Figs. 8 and 9 show the operating lever in plan and elevation, respectively; and Figs. 10, 11 and 12 the lock plan, side and front elevations, respectively.

Our invention relates to car couplers of the vertical plane type, such as are shown in Letters Patent of John Willison No. 1,201,665, dated October 17, 1916, and in a co-pending application of John Willison, Serial No. 727,851, filed July 24, 1924, in which the coupler comprises a coupler head, a lock and a suitable actuating mechanism for the lock. The present invention particularly comprises a novel means of lock-setting the lock and in so forming the lock, the lock operating mechanism and the cooperating parts of the coupler head that the movements of the lock into and out of lock-set position are extremely reliable, and when in lock-set position the lock is not easily dislodged or moved to another position. Our invention also comprises the various features which we shall hereinafter describe and claim.

Referring to the drawings, the coupler is comprised of a coupler head 2 having a buffing jaw 3, and a pulling jaw 4, connected by a buffing face 5 arranged on an axis inclined laterally to the line of draft. The pulling jaw 4 has a laterally extending recess 4^a to receive the complementary jaw 3 of the opposing coupler head, and its pulling face 7 engages a complementary face 8 on the buffing jaw on the opposing coupler head.

The lock 9 of the coupler operates in a pocket or cavity 10 which extends upwardly

and rearwardly from the buffing face 5 into the coupler head. The lock 9 has a locking head 11 and rearwardly extending tail which hooks over the through bolt 13 and is thereby retained in the cavity 10, and has also a sliding bearing on the top of the bolt 13 which steadies the lock.

On the buffing jaw side of the lock 9 is a recess or depression 14, in which a forwardly extending arm 15 of the actuating lever 16, which rotates on the bolt 13, operates to retract the lock either for uncoupling or lock-setting. The lever arm 15 terminates at its forward end in the surface 17, which cooperates with the bearing 19 at the upper side of the recess 14 in assisting in the moving of the lock into lock-set position, as is shown in Fig. 3. The lever arm has also a face 20 which engages the surface 21 at the rear of the depression 14 and upon rotation of the arm 15 retracts the lock to unlocked position, as is also shown in Fig. 3.

Upon the lowermost extremity of the lock is a projection 22 extending laterally toward the buffing jaw 3, which in normal locking and unlocking movements of the coupler head slides up and down in the inclined guiding groove 23 in the inner surface of the jaw 3. Above the groove 23 and in the same vertical plane is a recess or lock-set pocket 24 in the jaw 3 into which the projection 22 is intended to be tilted to bring the lock into lock-set position.

When the lock is in lowermost or locked position, as is shown in Fig. 1, and it is desired to place it in lock-set position, the lever 16 is rotated in a counter clockwise direction so that the face 20 engages the surface 21 of the lock and moves it rearwardly into unlocked position, in which the projection 22 is slightly to the rear of the pocket 24, and the lever arm surface 17 will then engage the bearing or point 19, as is shown in Fig. 3. As the bearing 19 is forward of the center of gravity of the lock the lower portion of the lock will swing forwardly just as soon as it is supported by the lever at the point 19, and this forward movement will swing the lock projection 22 into the pocket 24. When the uncoupling rod and lever have been released the lock will remain in lock-

set position supported at its forward end in the recess 24 and at its rear end by the bolt, as is shown in Figs. 4, 5 and 6.

The lower forward face of the lock 9 is bevelled at 25 so that when opposing couplers approximately at the same height from the track, and one of them is in lock-set position as is shown in Fig. 7, are drawn apart, the corner 26 of the lock 9 of the coupler A 10 in which the lock is in lowermost position will slide along the bevelled face 25 of the lock on the coupler B and squeeze or force it rearwardly, thus disengaging its projection 22 from the lock-set pocket 24, so that 15 as the couplers separate the lock in the coupler B will be free to drop down into lowermost position ready for coupling.

When, however, the opposing coupler is at a substantially different level than the coupler on the opposing car (for instance, where one car is loaded and the other is not) in extreme cases the corner 26 on one lock will not engage the bevelled face 25 of the other as the cars draw apart, and hence the lock 9 of the coupler B will remain in lock-set position. When the coupler B is again buffed by another coupler, either the buffing jaw or the lock of such opposing coupler will strike the lock and drive it rearwardly 30 out of its lock-set position and it will then drop down into lowermost or locked position.

The lock, at or near its lower edge, is provided with a lug 27 which extends toward the vertical interior wall 28 and is thereby maintained in vertical alignment and held from lateral movement. Another small projection 29 may also be added to the top of the lock to steady it against the upper part 40 of the wall 28.

The forward surface 17 of the lever arm 15 performs the function of acting with the bearing 19 as a fulcrum to shift the lock into lock-set position and in addition, it cooperates with the face 18 so as to limit effectively the rearward movement of the lock under high speed coupling impacts and thus prevent the lever from rotating under such impact, the lock from being thrown into lock-set position, or from being jammed into the rear of the lock cavity.

We have found that couplers constructed in accordance with our invention are extremely effective in coupling operations, as our improved mechanism not only prevents premature lock-setting, but also maintains the lock in lock-set position when the lock has been purposely placed in such position until it has been dislodged therefrom by the opposing coupler.

The terms and expressions which we have employed are used as terms of description and not of limitation, and we have no intention, in the use of such terms and expressions, of excluding any mechanical equiva-

lents of the features shown and described, or portions thereof, but recognize that various structural modifications are possible within the scope of the invention claimed.

What we claim is:

1. A car coupler having two rigid laterally-separated oppositely-disposed jaws; the coupler having a longitudinally-extending cavity therebetween; a lock movable in the cavity to assume a projected locking position, a retracted unlocking position and a lock-set position; cooperating means on the coupler and lock for supporting the lock in lock-set position; and lock actuating means arranged to move the lock into the retracted 75 unlocking position and into lock-set position.

2. A car coupler having two rigid laterally-separated oppositely-disposed jaws; the coupler having a longitudinally-extending cavity therebetween; a lock movable longitudinally in said cavity; a projection and recess engagement between said lock and coupler adapted to support the lock in lock-set position; and means for bringing the lock and coupler into such engagement. 85

3. A car coupler having two rigid laterally-separated oppositely-disposed jaws; the coupler having a longitudinally-extending cavity therebetween; a lock movable longitudinally in said cavity; a projection and recess engagement between said lock and coupler by which the lock is held in lock-set position; and means for rotating the lock to bring it into such engagement with said coupler. 95

4. A car coupler having two rigid laterally-separated oppositely-disposed jaws; the coupler having a longitudinally-extending cavity therebetween; a lock movable in said cavity; a projection on the lock engaging a recess in said coupler head during uncoupling and coupling movements; and a pocket communicating with said recess, the said projection being intended to enter said recess and thereby to support the lock in lock-set 105 position. 110

5. A car coupler having two rigid laterally-separated oppositely-disposed jaws; the coupler having a longitudinally-extending cavity therebetween; a lock movable longitudinally in said cavity; cooperating means on the lock and coupler for supporting the lock in lock-set position; and a lever arm arranged upon actuation to shift the lock to bring said cooperating means into engagement and the lock into lock-set position. 115

6. A car coupler having two rigid laterally-separated oppositely-disposed jaws; the coupler having a longitudinally-extending cavity therebetween; a lock movable longitudinally in said cavity; cooperating means on the lock and coupler for supporting the lock in lock-set position; a lever arm arranged upon actuation to shift the lock to bring said cooperating means into engagement and 125 130

the lock into lock-set position; and means connected with an opposing coupler head for tripping the lock from lock-set position.

7. A car coupler having two rigid laterally-separated oppositely-disposed jaws; the coupler having a longitudinally-extending cavity therebetween; a lock movable longitudinally in said cavity to assume projected locking, retracted unlocking and lock-set positions; an operating lever mounted on the coupler head one part of which is arranged upon actuation to move the lock from its projected locking to a retracted unlocking position, and one part of which acts as a fulcrum to shift the lock into lock-set position, and also to act as a stop to prevent the lock from moving, except under impulse of the lever, from its projected locking position to a fully retracted position.

8. A car coupling comprising like-to-like car couplers, each having two rigid laterally-separated oppositely-disposed jaws; each coupler having a longitudinally-extending cavity between its jaws, a lock movable in each said cavity having a projection and recess engagement with its coupler by which it is held in lock-set position, and means of tripping the said lock from its lock-set position, said means comprising the engagement of the said lock by the lock of the opposing coupler which removes the said lock from its lock set position by the relative movement of the locks as the couplers pull apart.

9. A car coupler comprising two rigid, laterally separated oppositely disposed jaws

having a longitudinally extending cavity therebetween; a lock movable longitudinally in said cavity; said lock being movable into lock-set position and being supported therein by means forming an operative part of the said coupler and being independent of the opposing coupler head, said lock being removed from said lock-set position by means of the lock of an opposing coupler head.

10. A car coupler comprising a head, a lock and lock operating means, said head having two rigid, laterally separated oppositely disposed jaws with a longitudinally extending cavity therebetween, said lock being movable longitudinally in said cavity to assume a projected locking position, a retracted unlocking position, and a lock-set position; and cooperating means on the lock and one of the aforesaid parts for supporting said lock in lock-set position.

11. A car coupler having two rigid laterally-separated oppositely-disposed jaws; the coupler having a longitudinally-extending cavity therebetween; a lock movable longitudinally in said cavity to assume projected locking and retracted unlocking positions; an operating lever mounted on the coupler head having a cam-shaped surface for slideable engagement with said lock, whereby the leverage for moving the lock to its retracted unlocking position is greater during the initial movement of the lock than during its final movement.
